ROOFING JOINT

Hans H. Doe, Milwaukee, Wis.

Application October 30, 1941, Serial No. 417,062

8 Claims. (Cl. 108—21)

Those types of roofing in which metallic roofing sheets have their side edges upturned or flanged, either to form a standing seam or a batten seam, have often not proven satisfactory because their construction has been such that sufficient free lengthwise movement due to contraction or expansion of the sheets has not been permitted. Also, in case of standing seam roofs, destructive total area horizontal movement has often been unintentionally allowed. Either of these faults lead to quick failure of the roof. Furthermore, the joints of the standing seam or batten seam roofing have been formed and finished on the job, making the labor cost for such roofing a large part of the total cost.

The objects of the present invention are to provide a roofing structure using roofing sheets of the flanged side type in which the adjoining upturned or flanged edges are joined together and protected from the weather by a joint structure which also holds the roofing sheets in their applied positions, but permits free lengthwise movement of each of the sheets, due to temperature change while preventing horizontal movement in any sheet from affecting or exerting pressure on the next adjoining sheet.

A further object of the invention is to provide a seamed type roofing structure in which the roofing sheets or plates are held down against the roof by clips fastened to the sheathing or rafters, and which has a snap on or slide-on pre-formed or partially pre-formed covering member which contacts with the sides of adjacent flanges of sheets or plates, thus reducing by a large percentage the labor required to install the roofing.

The invention further consists in the several features hereinafter set forth and more particularly defined by claims at the conclusion hereof.

In the drawings:

Fig. 1 is a perspective view of a roofing structure embodying the invention;

Fig. 2 is an enlarged detail vertical sectional view through the seam or joint;

Fig. 3 is a detail plan view of the joint, parts being broken away and parts shown in section;

Fig. 4 is a sectional view similar to Fig. 2 showing certain modifications;

Figs. 5, 6, and 7 are each sectional views similar to Fig. 2 showing other modifications;

Fig. 8 is a detail plan view of the joint shown in Fig. 7, parts being broken away and parts shown in section;

Fig. 9 is a view of the covering material in a preliminary form stage;

Fig. 10 shows certain modifications in the form of the base of the roofing sheet;

Fig. 11 is a vertical sectional view similar to Fig. 2 wherein the plates are spaced apart and their upturned edges associated with a batten strip;

Fig. 12 is a vertical sectional view similar to Fig. 11 showing certain modifications;

Fig. 13 is a detail vertical sectional view similar to Fig. 12 showing a modified form of joint partially completed;

Fig. 14 is a sectional view similar to Fig. 13 showing this joint completed.

Referring to Figs. 1 and 10 of the drawings, the roofing material is in the form of plain sheet metal 15 with upturned or flanged sides 16 as shown in Fig. 1 or of corrugated sheet metal body 17 with upturned or flanged sides 18 as shown in Fig. 10, the corrugations extending either vertically or horizontally of the sheet to reinforce the same. These sheets or plates are of certain definite lengths and are associated together lengthwise by overlapping the lower end of an upper plate with the upper end of a lower plate which upper end is secured to the frame of the roof by nails 19 or other suitable fastening. Lengthwise extending lengths of assembled plates are arranged next to similar sets of assembled plates at each side and are joined together at their upturned or flanged sides 16 by a joint structure embodying the invention. In Figs. 2 and 3 this joint structure includes a series of clips 20, fastening means for said clips, and a covering 21. The clips 20 are small curved sheet metal pieces punched to take two or more long nails 22 which are driven into the framework 23 of the roof, the nail heads exerting a clamping force on the clip which in turn by engaging the tops of the adjacent flanges 16 exerts a downward thrust thereon so as to keep said sheets or plates in proper vertical alignment without, however, preventing relative sliding movement between the clip and either of the sheets or plates engaged thereby, so that contraction and expansion of the metal roofing material due to changes of temperature may be taken care of without danger of having the roof buckle or of loosening the fastening means. To provide a weathering joint, cover members 21 are arranged to act as hoods to project down over the exposed upper ends of the flanges 16 and cover over the space between said flanges. This covering or the members 21 are formed by forming a sheet metal strip into generally channel shape form with the sides thereof reversely curved to form curved parts 24 and 25,

these channeled strips having overlapping engagement at their ends with each other as shown in Fig. 1, with the lowermost strip anchored at its upper end to the roof frame by a nail 26. These covering strips may be pre-formed, and the curved parts 24 and 25 will permit them to be secured in position by pushing them down over the clips 20, so that their curved edges 25 are free to snap into yielding engagement with the sides of the flanges 16 and into engagement with said clips at the curved parts 24 so as to connect them with the fastening means or nails 22. The connection of the covering member 21 with the flanges 16 permits relative movement between said strips and the flanges 16 of the roofing plate or section to compensate for any movement of these parts due to contraction or expansion of the metal thereof.

Instead of the form shown in Fig. 2 the cover strips 21' of generally channel form may be formed with longer sides having straight side portions 27 in engagement with the sides of the flanges 16 as shown in Fig. 4.

To keep the flanges a definite distance apart the clips 28 may have spaced lengthwise extending grooves 29 to receive the upper edges of the flanges, as shown in Fig. 5, these clips being secured similarly to the first form by the nails 30 and having cover strips 31 snapped thereover, similar to Fig. 2.

Another form of the joint is shown in Fig. 6 wherein the clip 32 is bent at its sides to form a flat top part 33 for the fastening means 34, and the cover strips 35 are formed to provide pointed ridges 36.

In the form shown in Figs. 7 and 8 the clip is formed to provide a tube 37 flanged at its bottom 38 and at its top 39, the fastening means 40 passing down through the tube and exerting pressure thereon to in turn put pressure on the flanges 16 of the roofing plates to hold them in position, the upper flange 39 of this clip forming a gripping ledge adapted to be engaged by the cover strip 41 which is generally similar to the cover strip 21 of Fig. 2 and having curved sides similar to the sides 25 and adapted to snap over the outer edges of the flanges 39 and engage the sides of the flanges 16.

The cover strips above described may be formed at the factory or in some instances cover strips initially formed to a readily stackable form as shown at 21^a, Fig. 9, may be finish formed during the assembly of the roof parts on the roof.

In those cases where it is desired to more widely separate adjoining sections of the roofing from each other as by a batten strip 43, the joints shown in Figs. 11 and 12 may be used. In Fig. 11 the clip 44 is secured to the top of the batten strip 43 by the nails 45 fastening said strip 43 to the roof frame 46, and a cover strip 47 extends over the top of the batten strip and the ends of clip 44 and has curved portions yieldingly engageable with the sides or the flanges 16.

The form shown in Fig. 12 is similar to that of Fig. 11 except that the clips 48 in this form are provided with spaced grooves 49 to receive the upper ends of the flanges 16. These clips are fastened to the roof and to the batten strip 50 by the nails 51 and the joint is covered and held in laterally aligned position by the cover strip 52.

The form shown in Figs. 13 and 14 is similar to that of Figs. 11 and 12 except that the cover strip 53 is formed to be slid onto the clips 48, 75

similar to the clips 48, and which are fastened to the roof and to the batten strip 54 by the nails 55. After the cover strip 48' is initially slid over the clips as shown in Fig. 13, this cover strip together with the clips are bent downwardly against the side flanges 16 of the roofing sheets or plates 15 as shown in Fig. 14.

In all of the above forms the upstanding edges of adjacent roofing sheets are free to move 10 lengthwise relative to each other and to the covering hoods for said edges.

I desire it to be understood that this invention is not to be limited to any particular form or arrangement of parts except in so far as such limitations are included in the claims.

What I claim as my invention is:

1. A joint structure for roofing in which the sheet metal roofing material has upturned flanged sides extending from its base at an obtuse angle comprising clamps having parts engaging the top edges of the spaced upturned sides of adjoining sections of said material at spaced intervals to exert a hold down pressure on said sections while permitting relative lengthwise movement between said sections and relative sliding movement between the clamps and said sections to permit contraction and expansion of said sections without danger of buckling of the roofing or of loosening said clamps, and covering means for the spaces between said sections having direct engagement with the sides of said upturned sides adjacent the top portion thereof whereby said roofing sections will be held down from the upper portions only of said upturned edges and are free to move lengthwise relative to each other and to said covering means.

2. A joint structure for roofing in which the sheet metal roofing material has upturned flanged sides extending from its base at an obtuse angle comprising clamps having parts engaging the top edges of the spaced upturned sides of adjoining sections of said material at spaced intervals to exert a hold down pressure on 40 said sections while permitting relative lengthwise movement between said sections and relative sliding movement between the clamps and said sections to permit contraction and expansion of said sections without danger of buckling 45 of the roofing or of loosening said clamps, and covering means for the spaces between said sections having interlocking engagement with said clamps and direct engagement with the sides of said upturned sides adjacent the top portion 50 thereof whereby said roofing sections will be held down from the upper portions only of said upturned edges and are free to move lengthwise relative to each other and to said covering means.

3. A joint structure for roofing in which metallic sheet roofing material has upturned flanged sides extending from its base portion at an obtuse angle comprising clips engaging the top edges of the spaced upturned sides of adjoining sections of roofing at spaced intervals, fastening means extending between said sections for securing said clips in operative position while permitting lengthwise shifting of said sections relative to each other and relative sliding movement between said clips and said sections to permit contraction and expansion of said sections without danger of buckling of the roofing or of the loosening of said clips, and covering means for the spaces between said sections having interlocking engagement with said clips and direct engagement with the sides of said upturned

sides adjacent the top thereof to permit adjacent roofing sheets moving lengthwise relative to each other and to said covering means.

4. A joint structure for roofing in which the sheet metal roofing material has upturned flanged sides extending from its base at an obtuse angle comprising clamps having parts engaging the top edges of the spaced upturned sides of adjoining sections of said material at spaced intervals to exert a hold down pressure on said sections while permitting relative lengthwise movement between said sections and relative sliding movement between the clamps and said sections to permit contraction and expansion of said sections without danger of buckling of the roofing or of loosening said clamps, and a cover strip having a snap-over connection with said clamps and direct yielding engagement with said upturned sides adjacent the top portion thereof to permit free lengthwise movement of said sections relative to each other and to said cover strip.

5. A joint structure for roofing in which metallic sheet roofing material has upturned flanged sides comprising clips engaging the upper edge portion of the spaced upturned sides of adjoining roofing sections at spaced intervals and extending laterally beyond said sides to hold down said sections while permitting relative sliding movement between said clips and either of the sections engaged thereby and movement of said sections relative to each other so that contraction and expansion of said sections may occur without danger of the roof buckling or of loosening said clips, batten strips interposed between the flanged sides of said sections and free of said sides carrying said clips and secured to the frame of the roof, and cover strips for the space between said adjoining sections completely covering the laterally extending portions of said clips and the tops of said batten strips and extending into engagement with said upturned sides.

6. A joint structure for roofing in which metallic sheet roofing material has upturned flanged sides comprising clips engaging the upper edge portion of the spaced upturned sides of adjoining roofing sections at spaced intervals and extending laterally beyond said sides to hold down said sections while permitting relative sliding movement between said clips and either of the sections engaged thereby and movement of said sections relative to each other so that contraction and expansion of said sections may occur without danger of the roof buckling or of loosening said clips, batten strips interposed between the flanged sides of said sections and free of said sides carrying said clips and secured to the frame of the roof, and cover strips for the space between said adjoining sections completely covering the laterally extending portions of said clips, the edges of said cover strips being bent with said clips to a position for direct engagement with said upturned sides.

7. A joint structure for roofing in which metallic sheet roofing material has upturned flanged sides comprising clips having spaced grooves engaging with the top edges of adjoining roofing sections at spaced intervals, fastening means for securing said clips in operative position, and a cover strip having an interlocking connection with said clips and a weather-tight connectiton with the sides of said flanges.

8. A joint structure for roofing in which metallic sheet roofing material has upturned flanged sides comprising clips having flanged ends and a tubular section connecting said ends, fastening means passing through the tubular section of each clip and securing it in clamping engagement with the flanged sides of adjoining roofing sections, and a cover strip engaging said clips and forming a covering for the space between said sections.

HANS H. DOE.
